RIFLE TROUGH

Alfred O. Hoffman, Oakland, Calif.

Application December 16, 1931, Serial No. 581,319

9 Claims. (Cl. 209—205)

The invention relates to improvements in the construction of riffle troughs wherein pulverized or finely divided solid material containing particles of the heavier precious metals is arranged to be conveyed in a stream of water flowing across a series of riffles for gravity settlement of the metal particles into collecting pockets of the riffle structure.

An object of the invention is to provide a riffle assembly of knock-down structure for permitting a replacement or substitution of riffle elements in the assembly thereof, said elements of general channel section.

Another object is to provide riffle pockets of improved section for insuring the segregation and retention of metal particles therein.

A further object is to provide for using side elements of the trough for defining and sealing the ends of the riffle pockets, said side elements separable from the riffle elements for permitting the aforesaid replacement or substitution of the latter elements.

The invention possesses other objects and features of advantage, some of which, with the foregoing, will be set forth or be apparent in the following description of a typical embodiment of the invention which is illustrated in the accompanying drawing, in which,

Figure 1 is a perspective side view of a riffle trough embodying the invention, a side element of the trough being shown fragmentarily and in displaced position.

Figure 2 is a sectional elevation through the trough when in condition for use, said section taken generally at the line 2—2 in Figure 1.

Figure 3 is a fragmentary full face view of a portion of the riffle structure of Figure 1, flow lines of the material passing thereover being indicated in the view.

Figure 4 is a fragmentary perspective view disclosing the interlocking engagement of riffle members of the structure.

As particularly illustrated, the features of the present invention are incorporated in the structure of a riffle trough comprising opposite side walls 5 and 6 having a series of riffles extending between them. A receiving apron 7 is provided at the upstream end of the riffle portion of the trough, said apron arranged to receive a water-borne and pulverized mixture containing metal particles for separation in the riffle pockets. By way of illustration, a trough spout 8 is fragmentarily shown as disposed (Figure 1) above the apron 7 for delivering the aforesaid mixture thereto. At the lower, or downstream, end of the

riffles, a discharge apron 9 is provided for receiving the material from which the metal particles have been separated in the riffle pockets.

The trough sides 5 and 6 extend upwardly from the sides 11 of a shallow box 12 of uniform width, said box providing a base for the riffle trough. The trough sides 5 and 6 preferably compose metal plates and are provided at their upper ends with inturned longitudinal flanges 13 disposed somewhat above the level of the 10 riffles. The flanges 13 are designed to minimize loss of material from the trough by splashing, may be used for supporting a grizzly or other accessory across the trough, and are understood to stiffen the side plates against bending or flexure longitudinally of the trough.

The riffles, it will now be noted, comprise a unitary assembly which provides a series of grooves extending transversely of the trough and terminating at the trough sides 5 and 6. Preferably, and as shown, said grooves terminate in common planes at the opposite sides of the riffle assembly whereby the latter may abut the inner faces of the trough sides 5 and 6 in said planes to form pockets of said grooves.

Means are provided for sealing the ends of the riffle grooves at the trough sides 5 and 6, and said means preferably comprise the provision of relatively soft facing elements 14 on the sides 5 and 6 and in opposition to the planar sides of the 30 riffle assembly. As particularly indicated, the facing elements 14 are of wood; it is to be understood however, that the same might be of other material such as fabric, rubber or cork compositions, etc. In this manner a pressure engagement of the trough sides with the riffle sides is arranged to more or less embed the ends of the riffle grooves thereat whereby leakless pockets are defined along the riffle assembly. In the present instance, the receiving and discharge 40 aprons 7 and 9 respectively are of the same width as the riffle assembly whereby they may also be sealedly engaged between the facing elements 14 of the trough sides.

While the riffle assembly constitutes a unit with 45 respect to its sealing between the trough sides 5 and 6, it is preferred to form said assembly of a plurality of independently formed riffle members of general channel form, said members being similar as to certain features thereof, and dissimilar 50 as to other features. As particularly illustrated, the first four riffle grooves at the upstream end of the riffle assembly are provided in like riffle members 15, six like riffle members 16 follow the members 15, and a single riffle member 17 com- 55

plete the riffle assembly. Grooves, or pockets, 18, 19 and 20 are respectively provided in the riffle members 15, 16 and 17, said grooves being of different shapes at the bottom portions thereof. 5 It will be understood that the number, order, and form of riffle members used in the assembly would vary with the nature of the material to be handled and with other factors of operation, and that the particular arrangement shown is 10 merely illustrative of one possible assembly of the riffle members.

Referring now more particularly to the structure of the riffle members, it is to be noted that each of these members is formed of suitable sheet 15 material, and that means are provided for directly interlocking the upper edges of opposed side walls of the adjacent members whereby said members cooperate to solely provide the trough bottom at the riffle assembly. By reference to 20 the form of the members 16, it is noted that each said member is provided with an upstream wall portion 21 and a downstream wall portion 22, said wall portions being mutually parallel and generally perpendicular to the longitudinal axis of the 25 trough. At the top of each wall 22, an integral apron portion 23 extends obliquely downwardly in a downstream direction, and a further and integral edge portion 24 is formed to provide an upwardly opening channel beneath the portion 23. 30 The free edge of the portion 24 is spaced from the apron 23 and from the downstream face of the wall 22 by a distance which is no less than the thickness of the material used to form the member 16; in this manner, a space 25 is defined 35 between the apron portion 23 and edge portion 24 and the top part of the wall 22. A downwardly turned and integral flange 26 is provided at the top of each wall 21, said flange shaped for engagement beneath an apron portion 23 and in 40 the space 25 whereby adjacent members 16 may be engaged and locked together against lateral separation thereof.

With the described interlocking means for the members 16, it will be clear that a flange 26 of a 45 given member 16 must be inserted from an end of the space 25 of the adjacent member 16 for effecting the assembly shown. The present assembly is seen to dispose the apron portions 23 in general enclosing relation to the flanges 26 50 and at the upstream edges of the riffle pockets, whereby leakage at the joints is minimized. It will now be noted that the downstream edges of the receiving apron 7 and of the riffle members 17 and 15 are also formed to define the spaces 25 55 at the downstream sides thereof. Flanges 26 are provided at the upstream sides of the members 17 and 15 and of the discharge apron 9 for insertion in appropriate spaces 25 of the different members. In this manner, the various members 60 15, 16 and 17 may be associated in any desired order or number with and between the receiving and discharge aprons 7 and 9 to provide a unitary bottom assembly for a riffle trough, said assembly being secured by and between the side 65 elements 5 and 6 in the previously described manner.

The side plate 5, it will now be noted, is longitudinally divided to define upper and lower portions 27 and 28 thereof. The lower plate portion 70 28 is fixed along a side of the base box 12 and the upper portion 27 is hinged to the portion 28 whereby the latter portion may be swung to and from its operative position against a side of the described riffle assembly; the swinging portion 27 is respectively shown in inoperative and opera-

tive positions in Figures 1 and 2. By reason of the displaceability of the plate 27, the placement or rearrangement of the riffle assembly is arranged to be facilitated.

With the side plates 5 and 6 both engaging 5 opposed sides of the described riffle and apron assembly, bolts 29 are engaged with and between the plates at spaced points therealong whereby a turning up of nuts 31 on the bolts may compress the said assembly between the relatively soft facing elements 14 for embedding the assembly sides in said elements to provide the desired degree of seal; as shown in Figures 1 and 2, more or less permanent grooves 32 are formed in the elements 14 as the result of the engagement of the elements 15 with the riffle and apron members of the trough bottom assembly. Preferably, and as shown, the bolts 29 define a single plane extending longitudinally of the trough and generally centrally through the riffle assembly whereby the 20 elements 14 are drawn against the sides of said assembly with uniform pressure. It will now be particularly noted that the sealing elements 14 are spaced from the bottom of the plates 5 and 6 whereby to permit any necessary bending of these 25 plates longitudinally therealong and laterally of the trough; in this manner, a proper application of the sealing elements is assured. If desired, cleats 33 may be provided along the inner sides of the plates 5 and 6 for supporting the trough 30 bottom assembly during the mounting thereof between the plates.

Referring now to the specific form of the riffle members 16, it is noted that the bottom of each said member comprises a planar and integral 35 portion 34 extending obliquely downwardly from the bottom edge of its downstream wall 22 to a point on the upstream side of the plane of its wall 21. The wall 21 extends slightly lower than the wall 22 and a flat bottom portion 35 extends 40 obliquely from the bottom edge thereof. The lower edges of the bottom portions 34 and 35 are integrally connected by a cylindrically curved portion 36 to complete the groove 19. Preferably, and as shown, the bottom portion 34 and 45 the apron 23 at the bottom and top respectively of the wall 22, each make forty-five degree angles with the plane of said wall. As brought out in Figure 3, the spacing of the walls 21 and 22 is such that when a series of members 16 are interlocked in the described manner, the plane of the apron 23 of one member will intersect the opposite wall 22 of the succeeding member substantially at the bottom of said wall and where the portion 34 joins it. 55

With the section of the groove 19 as shown and now described, the swirl produced in said groove as the water and ore mixture flows down the trough will centrifugally throw the heavier, and metallic, particles against the face of the bottom 60 portion 34 for gravity settlement along said wall to the bottom of the pocket, it being obvious that the heaviest said particles will ultimately reach the bottom of the groove. Preferably, and as shown, certain of the riffle pockets may contain 65 quicksilver 41 for amalgamation with gold or silver particles of the material being treated. Platinum particles are designed to be caught and retained solely by reason of their weight. In those riffle members 16 which are designed to receive the quicksilver, a valved outlet 42 pipe is provided for gravity discharge into a manifold pipe 43; in this manner, the unamalgamated quicksilver may be drawn off before the amalgamated mass is removed from the grooves 19. 75

The riffle member 17, it is noted, differs only from the member 16 in having a somewhat wider groove and a correspondingly altered bottom portion. This member is designed primarily to trap 5 any quicksilver or amalgam which may have been carried from the members 16 with the gangue. The bottom of the member 17 is also connected with the manifold pipe 43.

The riffle members 15 comprise upper walls 44 and 45 at the upstream and downstream sides thereof. A planar bottom wall 46 extends obliquely downwardly from the bottom edge of each wall 44, the latter said wall being of the same depth as the walls 22 of the members 16 and 15 the wall 46 defining the same angle with the wall 44 as that defined by the wall 34 with the wall 22 of the member 16. The planar wall 45 extends to a juncture with the wall 46 to complete the definition of the groove 18. The members 15, it is noted, function to segregate and retain the larger particles of the precious metal to be saved, and the action at the walls 46 corresponds to that at the bottom portions 34 of the members 16.

25 The unitary riffle trough structure now described, it is noted, may be suitably supported in an inclined position to provide a desired gradient for the flow of the material being treated; as particularly shown, blocks 51 and 52 support the structure in an inclined position. The described structure may, of course, be supported on a vibrating platform, or otherwise shaken, if such is desired. The base box 12, it is noted, may function to retain any liquid escaping from the 30 riffle assembly, a perforated plate 53 extending thereacross at its lower end for limiting the height to which the liquid may accumulate in the box.

From the foregoing description taken in connection with the accompanying drawing, the advantages of the construction and method of operation will be readily understood by those skilled in the art to which the invention appertains, and while I have described the principle of operation, together with the device which I now consider 45 to be the best embodiment thereof, I desire to have it understood that the device shown is merely illustrative, and that such changes may be made, when desired, as fall within the scope of the appended claims.

50 Having thus described my invention, I claim as new and desire to secure by Letters Patent of the United States the following:

1. In a riffle trough, a riffle structure comprising a bottom portion formed of sheet metal to provide collecting grooves extending transversely of the trough, longitudinal side members of the trough engaging said bottom portion at the ends of said grooves and presenting faces of yielding material thereagainst, tension rods cooperative 55 between said side members to clamp said bottom portion between them for embedding the side edges of the bottom portion in said faces to seal the groove ends, a supporting base beneath said trough and in spaced relation therefrom, and plates of resilient material extending upwardly from said base and directly carrying said side members.

2. In a riffle trough, a riffle structure comprising a bottom portion formed of sheet metal to 70 provide collecting grooves extending transversely of the trough, longitudinal side members of the trough engaging said bottom portion at the ends of said grooves and presenting faces of yielding material thereagainst, tension rods disposed in a common plane extending longitudinally and cen-

trally of said bottom portion and cooperative between said side members to clamp the bottom portion between them for embedding the side edges of the bottom portion in said faces to seal the groove ends, a supporting base beneath said 5 trough and in spaced relation therefrom, and plates of resilient material extending upwardly from said base and directly carrying said side members, one of said plates hinged to said base.

3. In a riffle trough, a riffle structure providing 10 a succession of grooves extending transversely in the trough bottom, forward and rear sides of said grooves planar and substantially perpendicular to the longitudinal trough axis, and corresponding bottom portions of said grooves planar and extending obliquely downwardly and rearwardly 15 from the bottoms of the forward groove sides.

4. In a riffle trough, a riffle structure providing a succession of grooves extending transversely in the trough bottom, forward and rear sides of said 20 grooves planar and substantially perpendicular to the longitudinal trough axis, and corresponding bottom portions of said grooves planar and extending obliquely downwardly and rearwardly 25 from the bottoms of the forward groove sides, said bottom portions making substantially forty-five degree angles with said forward groove sides.

5. In a riffle trough, a riffle structure providing a succession of grooves extending transversely in the trough bottom, forward and rear sides of said 30 grooves planar and substantially perpendicular to the longitudinal trough axis, and corresponding bottom portions of said grooves planar and extending obliquely downwardly and rearwardly 35 from the bottoms of the forward groove sides, and aprons provided at the tops of said groove sides and providing planar faces sloping downwardly and forwardly to define substantially forty-five degree angles with said groove sides.

6. In a riffle trough, a riffle structure providing 40 a succession of grooves extending transversely in the trough bottom, forward and rear sides of said grooves planar and substantially perpendicular to the longitudinal trough axis, and corresponding bottom portions of said grooves planar and extending obliquely downwardly and rearwardly 45 from the bottoms of the forward groove sides, said bottom portions making substantially forty-five degree angles with said forward groove sides, and aprons provided at the tops of said groove 50 sides and providing planar faces sloping downwardly and forwardly to define substantially forty-five degree angles with said groove sides, the planes of said apron faces intersecting the opposite wall of said grooves substantially at the 55 bottoms of said forward groove sides.

7. In an hydraulic riffle trough, a riffle structure providing a groove in the trough bottom extending thereacross, mutually opposed forward and rear side portions of said groove planar, bottom 60 portions of said groove planar and extending downwardly and rearwardly from the bottoms of said side portions, and a cylindrically concave bottom portion connecting the bottom edges of 65 the oblique bottom portions.

8. In an hydraulic riffle trough, a riffle structure providing a groove in the trough bottom extending thereacross, forward and rear side portions of said groove planar and substantially perpendicular to the longitudinal trough axis and with the rear side portion extending lower than the front side portion, and a bottom portion of said groove planar and extending obliquely downwardly and rearwardly from the bottom of the 70 75

forward groove side to a juncture with the rearward groove side at the bottom of the latter.

5. In an hydraulic riffle trough, adjacent one-piece channel elements shaped of sheet metal and disposed transversely of and defining the trough bottom thereat, the upper part of the downstream wall of a said element shaped to provide a top edge for the wall and an apron portion sloping downwardly from said edge in a downstream direction and a channel portion beneath said apron opening upwardly and spaced from the wall, and
- 10

the upper part of the upstream wall of the element adjacent and at the downstream side of the first element shaped to provide a top edge for the wall and a depending portion spaced from the wall at its downstream side and arranged for engagement in the said channel portion of the first element whereby said walls are mutually interlocked against mutual separation transversely of the plane of the trough bottom.

10

ALFRED O. HOFFMAN.
